DEMOUNTABLE WINDOW SHADE BRACKET

Gustav B. Winter, Hempstead, N. Y.

Application August 15, 1940, Serial No. 352,778

5 Claims. (Cl. 248—269)

This invention relates to a demountable window shade bracket and particularly to a bracket adapted to be demountably attached to the upper sash of a window and which may be removed therefrom without removal of the supporting fastenings of the bracket for washing the window.

More particularly, it is an aim of the invention to provide a bracket having wedge means for engaging the inner side of the lower sash of the window for limiting the movement of the lower sash in a direction toward the bracket by wedging the lower sash into binding engagement with the window frame to thereby prevent the bracket and window shade from being damaged or dislodged by the lower sash being moved to a fully raised position.

Still a further aim of the invention is to provide a bracket having means for supporting a window shade roller so that the free end of the shade will extend downwardly from the outer instead of the inner side of the roller to thereby space the window shade outwardly from the lower, inner sash of the window.

Still another aim of the invention is to provide a window shade bracket having means for mounting either end of a window shade roller.

Other objects and advantages of the invention will hereinafter become more fully apparent from the following description of the drawing, which illustrates a preferred embodiment of the invention, and wherein—

Figure 1 is a fragmentary elevational view looking toward the inner side of a window and showing a window shade mounted on the upper sash of the window by means of a pair of the brackets.

Figure 2 is an edge view in elevation of the upper portion of the window showing one of the brackets in side elevation.

Figure 3 is a front elevational view of the bracket shown in an applied position.

Figure 4 is a vertical sectional view taken substantially along the plane of the line 4—4 of Figure 3, and

Figure 5 is a perspective view of the bracket.

Referring more particularly to the drawing, wherein like reference characters designate like or corresponding parts throughout the different views, 10 designates generally a portion of a conventional window including a portion of the frame 11 in which is slidably mounted an upper sash 12 and a lower sash 13. The numeral 14 designates a conventional window shade which is mounted on a conventional spring shade roller

15 in a conventional manner. These parts are shown and described merely to illustrate the application of the window shade bracket, designated generally 16 and which comprises the invention.

The bracket 16 includes an elongated base portion 17 from one edge of which projects a flange 18 which is disposed substantially at a right angle to the base 17. The base 17 extends beyond the lower end of the flange 18 and the extended portion thereof is turned back at 19 to form the portion 20. The lower end of the flange 18 is flared outwardly and then tapered downwardly to form the flange portion 21. The opposite edge of the base 17 is provided with a corresponding flange portion 22 disposed in opposed relationship to the flange portion 21. Portion 20 rests on the outer edges of the portions 21 and 22 and combines therewith to form a wedge, designated generally 23.

The base 17 is provided with a keyhole slot 24 adjacent its lower end and behind the turned back portion 20 and is also provided with a transverse slot 25 adjacent its upper end which extends toward and opens into a semi-circular recess 26 in the flange 18.

Flange 18 is provided with an extension at its upper end forming an arm 27 adjacent the outer end of which is provided a slot 28 and an aperture 29. Slot 28 is provided with a restricted upper portion 30 which opens outwardly of the upper edge of the arm 27 and with a downwardly converging portion therebeneath which forms a shoulder 31.

The bracket 16 is adapted to be mounted on the upper sash 12 by means of a pair of headed screws 32 and 33, the heads of which are spaced from the sash a distance slightly greater than the thickness of the plate 17. The bracket 16 is applied by passing the enlarged end of the keyhole slot 24 over the head of the screw 32 and then moving the bracket upwardly so that the shank of the screw 32 will engage the lower restricted portion of the keyhole slot 24. The bracket 16 is then swung to cause the opening 27 to receive the head of the screw 33 through which opening the head passes by a swinging movement of the bracket 16 to cause the shank of the screw 33 to engage the slot 25 to thereby detachably mount the bracket 16 on the screws 32 and 33 in the position, as best illustrated in Figure 3. The base portion 17 extends inwardly or toward the center of the sash 12, relatively to the flange 18, and it is to be understood that a similarly constructed bracket 16

is mounted on the opposite or right hand side of the sash 12, as illustrated in Fig. 1. The last mentioned bracket 16 is reversed in respect to the positions of the base 17 and flange 18, so that each of the brackets 16 will have their base portions 17 extending toward the center of the sash 12. The shade roller 15 is then mounted on the two brackets 16 which the flat shank end of the shade roller engaging the slot 28 of one of the brackets and the round shank end of the roller engaging the aperture 29 of the other bracket. The roller 15 will prevent the brackets 16 from moving toward one another and will therefore prevent the brackets from becoming disengaged from their fastenings 32 and 33 while the roller is attached thereto. The shade roller 15 is preferably reversed end for end from the normal manner in which it is mounted so that the shade 14 will extend downwardly from the outer side of the roller instead from the inner side thereof to thereby space the shade 14 outwardly a sufficient distance so that it will not engage the lower sash 13. However, by providing each of the brackets 16 with a slot 28 and aperture 29 the roller may be mounted as just previously described or in the conventional manner so that the shade will extend downwardly from the inner side of the roller. The shoulder 31 is adapted to engage above the flat shank end of the roller 15, not shown, to prevent said end from becoming accidentally disengaged from the bracket in which it is mounted.

From the foregoing it will be obvious that the bracket 16 may be readily mounted, as just previously described, after which the roller 15 carrying a shade 14 may be applied in the manner previously described and as shown in Figures 1 and 2. By thus mounting the shade 14 on the upper sash said sash may be lowered to permit ventilation through the top of the window and the shade 14 drawn with the upper sash 12 in a lowered position for shading the portion of the window opening beneath the upper end of the upper sash. Should the lower sash be pushed upwardly too far its side, which is adjacent the upper sash, will contact the wedge portions 23 which will force the lower sash 13 inwardly and into binding engagement with the sash guides of the window frame 11 to prevent further upward movement of the sash 13 and to prevent the brackets 16, the shade and shade roller from being damaged or dislodged by the lower sash. The window shade and roller may be readily removed in the conventional manner after which the brackets 16 may be swung inwardly of one another to disengage them from the fastenings 33 and then moved downwardly to disengage them from the fastenings 32 to detach the brackets 16 so that the window may be moved to any desired position for washing.

Various modifications and changes are contemplated and may obviously be resorted to as only a preferred embodiment of the invention has been disclosed.

I claim as my invention:

1. A window shade bracket comprising a bracket having a base portion and a flange portion projecting outwardly from the upper part of the base portion, said flange portion being disposed at the outer edge of the base portion, said base portion being provided with a keyhole slot, adjacent its lower end for engaging a headed fastening, said base portion being provided with a transverse slot in its upper end, said flange

having a semicircular recess through which one end of said transverse slot extends to open outwardly of the outer edge of the base portion, for receiving a second headed fastening for detachably mounting said bracket, and said flange being provided with means for supporting one end of a window shade roller.

2. A bracket as in claim 1, said window shade bracket being adapted to be mounted on a side rail of the upper sash of a sliding sash window with the entire base portion thereof resting flush thereagainst, and said bracket being provided with wedge means at its lower end for engaging the inner side of the lower sash of the window for wedging the lower sash against the sash frame for limiting the upward movement of the lower sash relatively to the upper sash.

3. A window shade bracket having a relatively wide base portion provided with means for detachably engaging headed fastenings for detachably mounting the bracket on the upper sash of a window with the entire base portion flush thereagainst, wedge means formed integral with the lower end of the bracket and extending the width of the base portion, for engaging the inner side of the lower sash of the window for limiting the movement of the lower sash in a direction toward the bracket, and brace members projecting outwardly from the base portion and engaging the inner side of the wedge means for rigidly supporting the wedge means relatively to the base portion.

4. A window shade bracket of the type which is adapted to be mounted on the side rail of an upper window sash, comprising an elongated relatively wide base portion adapted to be disposed against the sash rail, said base portion having a keyhole slot adjacent its lower end adapted for receiving the head of a fastening disposed in said rail, a flange projecting outwardly from the outer longitudinal edge of the base portion and provided with an opening, said flange being disposed adjacent the upper end of the base portion, a transverse slot, adjacent the upper end of the base portion, opening outwardly through the opening in the flange and adapted for receiving a second headed fastening, when the first fastening is disposed at the lower end of the keyhole slot, said first mentioned fastening and keyhole slot forming a pivot by which the upper end of the bracket can be swung outwardly of the rail to engage the second fastening and inwardly for disengagement therefrom.

5. A window shade bracket of the type which is adapted to be mounted on the side rail of an upper window sash, comprising a bracket having a portion for engaging and mounting an end of a window shade roller, said bracket having a base portion adapted to be attached to a side rail of a window sash, and a flange portion projecting outwardly from one longitudinal edge thereof, the lower end of said base portion being turned back upon itself to form a relatively wide wedge member, said wedge member being inclined downwardly and inwardly relatively to said rail, a portion of said flange portion being disposed under a side edge of the wedge member to provide a support for said side edge, and the other edge of the base member being provided with an outwardly projecting flange portion disposed beneath and engaging the wedge member to provide a support for the opposite longitudinal edge of the wedge member.
